UNITED STATES PATENT OFFICE.

EGBERT H. GOLD, OF EVANSTON, ILLINOIS.

TRAIN-PIPE END VALVE.

Application filed September 7, 1926. Serial No. 133,982.

This invention relates to improvements in end train pipe valves for steam car-heating systems.

Systems of car heating using steam from the engine are constructed with a train line or main supply pipe extending from the boiler head in the engine cab to the rear of the train. This train line is connected by steam couplers between the cars and is provided with branch steam connections to the heating pipes in each car. Each end of the train pipe on each car is provided with an end train pipe valve, these valves at the adjacent ends of the two cars being normally open when the cars are included in a train and the steam couplings are connected in place. Only the end train pipe valve at the rear end of the train will be closed.

As the entire train line and connections are exposed to the weather, it naturally follows that considerable condensation takes place therein, and most of this condensate can only escape at the rear of the train line. This condensation, if it is not allowed to discharge at the rear as fast as it collects, will quickly freeze up and cause very serious trouble in cold weather. However, if the steam pressure is maintained on the train line all the way to the rear and the rear train pipe valve allowed to "bleed" a little steam through the rear hose, that is allow a small stream of steam to continuously escape, this common trouble will be avoided.

When the steam couplings between adjacent cars are connected, the workman standing adjacent the valves may move them to open position. However, it is sometimes desirable to open these valves from the platform above, for example, when steam is to be cut off from the entire train line, at which time the rear train pipe valve is opened wide to blow out the train line and allow all steam to escape.

The general object of this invention is to provide an improved form of end train pipe valve adapted to perform in a more satisfactory manner the functions noted hereinabove. The usual form of train pipe end valve is adapted to be mounted at the extreme end of the car train pipe, and is provided with an inlet connection adapted to be joined horizontally to the end of the train pipe, and an outlet connection through the lower portion of the valve casing adapted to connect with the coupling hose or equivalent

flexible coupling. The present type of end train pipe valve is adapted to be inserted in the car train pipe at some small distance from the end of the pipe, and is provided with horizontally aligned inlet and outlet ports at its two sides, with which the adjacent sections of the car train pipe are connected. A valve seat is provided in the casting in line with the outlet port, and a disk-shaped valve member is slidable edgewise vertically, similar to a gate-valve, to or from a position in engagement with the valve seat to close the valves. Guides are provided in the valve casing for this slidable valve member. The valve member is freely rotatable about its own axis so that it may seat correctly, and it is held seated by the steam pressure in the valve casing.

Another object is to provide a plurality of bleeding valves or ports in the valve members, all of which are normally closed by the valve seat when the valve member is in valve closing position, but one only of these ports being opened to permit the passage of a small stream of steam when the valve member is moved slightly from its completely closed position, but not moved sufficiently to open the main valve.

Another object is to provide improved means for moving this slidable valve member into or out of valve closing position, and for locking the same in open position.

Another object is to provide improved means for counter-balancing the valve member, so that it will remain in any partially open position to which it may be moved.

Another object is to provide a valve of this type which is compact and simple, and easily assembled.

Other objects and advantages of this invention will be apparent from the following detailed description of one approved form of the apparatus.

In the accompanying drawings: 100

Fig. 1 is a vertical central section through the valve, the view being taken substantially on the line 1—1 of Fig. 4.

Fig. 2 is a transverse vertical section, taken substantially on the line 2—2 of Fig. 1.

Fig. 3 is a horizontal section taken substantially on the line 3—3 of Fig. 2.

Fig. 4 is an end elevation, taken in line with the car train pipe.

Fig. 5 is a perspective view of the movable valve member.

The end of the main portion of the car

train pipe is shown at 1, and 2 is a short extension of this car train pipe leading from the end train pipe valve 3 to the flexible coupling member for making connections with an adjacent car. The main valve casing 3 is provided with aligned inlet and outlet ports 4 and 5, the pipe extension 2 screwing directly into the outlet port 5, and the car train pipe 1 being connected with inlet port 4 by means of the interposed bushing 6. Casing 3 comprises an upwardly projected extension 7 closed at the top by a screw cap 8. This extension provides for the movement of the valve member out of valve closing position, and the removable cap 8 permits the insertion or removal of the movable valve parts. A second extension 9 at one side of casing 3 houses one end of the valve operating lever 10, and the rock-shaft 11 to which this lever is secured. A stud 12 at the inner end of shaft 11 is journaled in an enlargement 13 of casing extension 9, and a bonnet 14 screwed into the opposite side of casing extension 9 provides a second bearing 15 for the shaft 11. The stuffing box 16 screwed into the bonnet 14 provides further bearing surfaces for the shaft 11 and also adjustably holds in place the packing 17 for preventing the escape of steam around the shaft.

The annular valve seat 18 is screwed into the inner end of the outlet passage 5. The movable valve member 19 is slidable vertically, like a gate-valve, along the guides 20 provided in the valve casing 3. This valve member 19 comprises a pair of circular plates or disks 21 and 21^a, connected in parallel spaced relation by the axial stem 22. The larger disk 21^a is merely a guide member and is provided with a series of relatively large openings 23 so as not to materially impede the passage of steam therethrough at any time. The valve plate 21 is adapted to seat against the valve seat 18, when in the position shown in the drawings, and completely closes the outlet port 5. The valve plate 21 is provided with a plurality (preferably 4 as here shown), of small bleeding ports 24, equally spaced about the peripheral portion of the circular plate. When the valve is closed, as shown in the drawings, these bleeding ports will all be closed by the valve seat 18. If, however, the movable valve member is raised slightly from the position shown, but not sufficient to completely unseat any portion of the valve plate 21, some one of these bleeding ports will be uncovered so as to permit the passage of a small stream of steam through the valve. At this time, the other bleeding ports 24 will remain closed by engagement with valve seat 18, or will be moved above the valve seat into the interior of the upper portion 7 of the valve casing. The disk-like movable valve member 19 is freely rotatable at all times

about its own axis so that it may seat correctly against the valve seat 18, and it will be held in this position by the steam pressure existing within the valve casing.

The free end of the valve lever 10 is forked to engage about the valve stem 22, whereby swinging movement of lever 10 will effect the raising or lowering of the movable valve member 19. The lower arm 25 of the forked portion of the lever is provided with a surface 26 engaging beneath the stem 22 to lift the valve member, this surface terminating in a shouldered recess 27 in which the steam 22 is engaged when the valve member is completely raised (as shown in dotted lines Fig. 2), whereby the valve is locked in opened position. The weight of the movable valve member resting in this shouldered recess 27 will normally prevent downward movement of the valve lever 10. However, the valve lever 10 may be positively swung downwardly when power is applied to the rock-shaft 11 (as hereinafter described), so that the recess 27 will be drawn away from the stem 22 and permit the lever and movable valve member to be lowered. At this time, the upper curved arm 28 of the fork of the lever will engage the upper surface of valve stem 22 and positively push the movable valve member 19 down into its valve closing position. The upwardly curved surface 29 of this arm 28 permits movement of the valve stem 22 out of the recess 27, and will at all positions in the swinging movement of lever 10 so engage the stem 22 as to urge same vertically downward.

A bellcrank lever 30 is keyed on the outer end of rock-shaft 11, being secured in place by cotter pin 31. The long arm 32 of this lever is adapted to be pivotally joined at 33 with the connections for operating the valve from a distance. The other arm 34 of the bellcrank carries a weight 35 adapted to counter-balance the weight of the movable valve member 19 and the lever 10 so that all of the parts carried by the operating shaft 11 will tend to remain in any position to which they may be moved.

The removable cap 8, bushing 6, and bonnet 14, permit the machining of all interior portions of the valve casing where same is necessary, and permits the ready insertion or removal of all interior movable portions of the valve mechanism.

When connected in service, with the car which carries this valve serving as one of the interior units of a train, the valve will normally be in open position as indicated in dotted lines in Fig. 2. A free passage of steam will then be permitted directly through the aligned pipe sections 1 and 2 and the valve casing 3. The movable valve member 19 will be locked in its elevated position by the engagement of the valve stem 22 in the locking recess 27, there being no material tend-

ency for the parts to drop from this position since they are counterbalanced by the weight 35. If this valve is located at the rear end of a train, so that it is necessary to 5 close the valve, the parts will be moved to the positions indicated in full lines in the drawings. In this position, the passage of steam will be completely cut off by the valve plate 21 seated against the valve seat 18. 10 The movable valve member is held securely in this position by the steam pressure within the valve casing. If it is desired to "bleed" the valve, that is permit the continual passage of a small flow of steam therethrough, 15 the valve mechanism is manipulated to slightly raise the movable valve member so that some one of the bleeding ports 24 will be uncovered. Since the circular valve member 19 is freely rotatable within the valve 20 casing, it may assume any position of angular adjustment against the valve seat 18, but some one of the bleeding ports 24 will always be so positioned that it will be uncovered when the movable valve member is slightly 25 raised from the completely closed position shown in the drawings. The movable valve member will remain indefinitely in this "bleeding" position, due to the friction of the parts, and due to the fact that the movable parts are all counterbalanced.

I claim:

1. An end train pipe valve comprising a casing, a valve seat therein, a disk-shaped valve member cooperating with the valve seat and bodily movable edgewise into or out of valve closing position, the valve member being freely rotatable about its own axis, there being a plurality of bleeding ports spaced at intervals through the edge 40 portion of the valve member, which ports are all closed by the valve seat when the valve member is in complete valve closing position.

2. An end train pipe valve comprising a casing, a valve seat therein, a disk-shaped valve member cooperating with the valve seat and movable edgewise into or out of valve closing position, the casing being formed with guideways for the valve member, the valve member being freely rotatable about its own axis, there being a plurality of bleeding ports formed in the edge portion of the valve member, which ports are all closed by the valve seat when the valve member is 50 in valve closing position; but some one of the ports being opened when the valve member is moved slightly from valve closing position.

3. An end train pipe valve comprising a casing, a valve seat therein, a disk-shaped valve member comprising a pair of parallel circular plates connected by an axial stem, one of the plates being formed to cooperate with the valve seat to close the valve, and 55 the other plate being perforated to permit

the free passage of steam therethrough, means in the casing for guiding the valve member for edgewise movement to or from a valve closing position, and means extending loosely between the plates and loosely engaging the stem for moving the valve. 70

4. An end train pipe valve comprising a casing, a valve seat therein, a disk-shaped valve member comprising a pair of parallel circular plates connected by an axial stem, 75 one of the plates being formed to cooperate with the valve seat to close the valve, there being a plurality of bleeding ports in this plate which are closed by the valve seat when the valve member is in complete valve closing position, and the other plate being perforated to permit the free passage of steam therethrough, means in the casing for guiding the valve member for edgewise movement to or from a valve closing position, and means loosely engaging the stem for moving the valve. 80

5. An end train pipe valve comprising a casing, a valve seat therein, a valve member movable in the casing to or from a valve closing position, bleeding ports in the valve member closed by the valve seat when the valve member is in complete valve closing position; but one of which ports is opened when the valve member is partially moved from this valve closing position, means for moving the valve member, and means for counterbalancing the valve member whereby it will remain in partially opened position. 90

6. An end train pipe valve comprising a casing, a valve seat therein, a valve member movable in the casing to or from a valve closing position, bleeding ports in the valve member closed by the valve seat when the valve member is in complete valve closing position; but one of which ports is opened when the valve member is partially moved from this valve closing position, a rock-shaft pivoted in the casing, a lever on the shaft for moving the valve member, a counterbalance for the valve member also mounted on the shaft, and means for rocking the shaft. 100

7. An end train pipe valve comprising a casing, a valve seat therein, a valve member movable in the casing to or from said seat, an operating lever having a forked end portion engaging a part of the valve member to positively move the member to open or closed positions, one arm of the fork having a locking shoulder which engages the valve member to hold the member in open position. 110

8. An end train pipe valve comprising a casing, a valve seat therein, a valve member movable vertically in the casing to or from a valve closing position, the valve member having a reduced neck portion, an operating lever having a forked end engaging about the neck, the lower arm of the fork serving to raise the valve member, and hav- 115 120 125 130

ing a neck-engaging recess for holding the valve member in raised position, the upper arm of the fork serving to engage the neck and move the valve member positively to closed position.

9. An end train pipe valve comprising a casing, a valve seat therein, a valve member movable vertically in the casing to or from a valve closing position, the valve member having a reduced neck portion, an operating lever having a forked end engaging about the neck, the lower arm of the fork serving to raise the valve member, and having a neck-engaging recess for holding the valve member in raised position, the upper arm of the fork being curved so as to engage the neck and positively move the valve vertically downward to valve closing position as the lever is swung about its pivot.

10. An end train pipe valve comprising a casing, a valve seat therein, a valve member movable vertically in the casing to or from a valve closing position, an operating lever having a forked end portion engaging a part of the valve member to positively move the member to open or closed positions, one arm of the fork having a locking shoulder which engages the valve member to hold the member in open position, and means for counterbalancing the weight of the valve member and operating mechanism in any position of adjustment.

11. An end train pipe valve comprising a casing, a valve seat therein, a valve member movable vertically in the casing to or from a valve closing position, an operating lever having a forked end portion engaging a part of the valve member to positively move the member to open or closed positions, one arm of the fork having a locking shoulder which engages the valve member to hold the member in open position, a rock-shaft to which the lever is secured, means for rocking the shaft, and a weighted lever mounted on the

shaft for counterbalancing the movable valve member and operating mechanism.

12. An end train pipe valve comprising a casing, a valve seat therein, a disk-like valve member comprising a pair of parallel circular plates connected by an axial stem, one of the plates being formed to cooperate with the valve seat to close the valve, and the other plate being perforated to permit the free passage of steam therethrough, means in the casing for guiding the valve member for edgewise movement to or from its valve closing position, a rockshaft in the casing, a lever secured to the shaft and having a forked end engaging about the stem of the movable valve member, one arm of the fork having a stem-engaging recess for locking the valve member in open position, means for rocking the shaft, and means secured to the shaft for counterbalancing the movable parts.

13. An end train pipe valve comprising a casing, a valve seat therein, a disk-like valve member comprising a pair of parallel circular plates connected by an axial stem, one of the plates being formed to cooperate with the valve seat to close the valve, there being a plurality of bleeding ports in this plate which are closed by the valve seat when the valve member is in complete valve closing position, and the other plate being perforated to permit the free passage of steam therethrough, means in the casing for guiding the valve member for edgewise movement to or from its valve closing position, a rockshaft in the casing, a lever secured to the shaft and having a forked end engaging about the stem of the movable valve member, one arm of the fork having a stem-engaging recess for locking the valve member in open position, means for rocking the shaft, and means secured to the shaft for counterbalancing the movable parts.

EGBERT H. GOLD.
